(57) **ABSTRACT**

Various exemplary embodiments relate to a filter configured to operate in an operational frequency range. The filter may include a mainline, at least one combline resonator coupled to the mainline, an input port coupled to the mainline, and an output port coupled to the mainline. The mainline may include at least one non-resonant node. The at least one non-resonant node may be configured to resonate in a frequency range outside of the operational frequency range of the filter, and the at least one combline resonator may be configured to resonate in a frequency range within the operational frequency range of the filter.

NON-RESONANT NODE FILTER

TECHNICAL FIELD

Various exemplary embodiments disclosed herein relate generally to cavity filters for radio, microwave, or other high frequency signals.

BACKGROUND

Cavity structures may act as resonant circuits for electromagnetic signals. One or more cavities may be combined to create a filter.

SUMMARY

A brief summary of various exemplary embodiments is presented. Some simplifications and omissions may be made in the following summary, which is intended to highlight and introduce some aspects of the various exemplary embodiments, but not to limit the scope of the invention. Detailed descriptions of exemplary embodiments adequate to allow those of ordinary skill in the art to make and use the inventive concepts will follow in later sections.

Various exemplary embodiments relate to a filter configured to operate in an operational frequency range, including: a mainline comprising at least one non-resonant node, wherein the at least one non-resonant node is configured to resonate in a frequency range outside of the operational frequency range of the filter; at least one combline resonator coupled to the mainline, wherein the at least one combline resonator is configured to resonate in a frequency range within the operational frequency range of the filter; an input port coupled to the mainline; and an output port coupled to the mainline.

In some embodiments, the mainline comprises at least two non-resonant nodes. In some embodiments, the filter further includes at least two combline resonators, wherein a first combline resonator is coupled to a first non-resonant node, and a second combline resonator is coupled to a second non-resonant node. In some embodiments, the filter rejects a first range of frequencies within the operational frequency range based on a first tuning of the filter, and wherein the filter rejects a second range of frequencies within the operational frequency range based on a second tuning of the filter. In some embodiments, the at least one non-resonant node and the at least one combline resonator are integral to the filter.

Various exemplary embodiments further relate to a method for manufacturing a filter configured to operate in an operational frequency range, the method including: forming a mainline comprising at least one non-resonant node, wherein the at least one non-resonant node is configured to resonate in a frequency range outside of the operational frequency range of the filter; forming at least one combline resonator coupled to the mainline, wherein the at least one combline resonator is configured to resonate in a frequency range within the operational frequency range of the filter; forming an input port coupled to the mainline; and forming an output port coupled to the mainline.

In some embodiments, the mainline comprises at least two non-resonant nodes. In some embodiments, the method further includes forming at least two combline resonators, wherein a first combline resonator is coupled to a first non-resonant node, and a second combline resonator is coupled to a second non-resonant node. In some embodiments, the filter rejects a first range of frequencies within the operational frequency range based on a first tuning of the filter, and

2

wherein the filter rejects a second range of frequencies within the operational frequency range based on a second tuning of the filter. In some embodiments, the at least one non-resonant node and the at least one combline resonator are integral to the filter.

BRIEF DESCRIPTION OF THE DRAWINGS

In order to better understand various exemplary embodiments, reference is made to the accompanying drawings, wherein:

FIG. 1 illustrates an embodiment of a conventional combline filter;

FIG. 2 illustrates an example of the frequency response of a conventional combline filter;

FIG. 3 illustrates an embodiment of a conventional notch filter;

FIG. 4 illustrates an example of the frequency response of a conventional notch filter;

FIG. 5 illustrates an embodiment of a non-resonant node filter;

FIG. 6A illustrates an example of the frequency responses of the non-resonant node filter; and

FIG. 6B illustrates another example of the frequency responses of the non-resonant node filter.

DETAILED DESCRIPTION

Referring now to the drawings, in which like numerals refer to like components or steps, there are disclosed broad aspects of various exemplary embodiments.

FIG. 1 illustrates an embodiment of a conventional combline filter 100. The conventional combline filter 100 may include eight combline resonators 102a-102h. A signal may be input to the combline resonator 102a via an input port 101. A filtered signal may exit the combline resonator 102h via an output port 103. Seven mainline coupling elements 104a-104g may couple the eight combline resonators 102a-102h. Four cross-coupling elements 106a-106d may couple pairs of combline resonators. Cross-coupling element 106a may couple combline resonator 102d and combline resonator 102d. Cross-coupling element 106b may couple combline resonator 102b and combline resonator 102d. Cross-coupling element 106c may couple combline resonator 102e and combline resonator 102h. And cross-coupling element 106d may couple combline resonator 102f and combline resonator 102h.

While eight combline resonators, seven mainline coupling elements, and four cross-coupling elements are shown, the number of combline resonators, mainline coupling elements, and cross-coupling elements may vary based on a desired capability of the conventional combline filter 100.

The mainline coupling elements 104a-104g and the cross-coupling elements 106a-106d may be positive or negative depending on a desired frequency rejection. For example, if greater frequency rejection is desired for frequencies above the passband of the combline filter 100, then the mainline coupling elements 104a-104g and the cross-coupling elements 106a-106d may all be positive. If greater frequency rejection is desired for frequencies below the passband of the combline filter 100, then the seven mainline coupling elements 104a-104g may be positive, cross-coupling elements 106a and 106c may be positive, and cross-coupling elements 106b and 106d may be negative.

FIG. 2 illustrates an example of the frequency response of a conventional combline filter. A passband region 202 may be a range of frequencies that are not significantly filtered by the

comline filter. A rejection region **204** may be a range of frequencies that are minimized by the comline filter. The example of FIG. 2 illustrates a comline filter with greater frequency rejection above the passband region **202**.

Achieving a desired frequency rejection near a passband with the conventional comline filter **100** may require precise design of the four cross-coupling elements **106a-106d** and other filter components. Due to the precise design requirements, the conventional comline filter **100** may have a complex and time-consuming assembly process.

FIG. 3 illustrates an embodiment of a conventional notch filter **300**. The conventional notch filter **300** may include five comline resonators **302a-302e** arranged in a notch configuration. Each of the five comline resonators **302a-302e** may be coupled to a transmission line **304** by five coupling strips **306a-306e**. A signal may be input to the transmission line **304** via an input port **308**. A filtered signal may exit the transmission line **304** via an output port **310**.

While five comline resonators and five coupling strips are shown, the number of comline resonators and coupling strips may vary based on a desired capability of the conventional notch filter **300**.

FIG. 4 illustrates an example of the frequency response of a conventional notch filter. A passband region **402** may be a range of frequencies that are not significantly filtered by the comline filter. A rejection region **404** may be a range of frequencies that are minimized by the notch filter. The example of FIG. 4 illustrates a notch filter with greater frequency rejection below the passband region **402**.

The comline resonators **302a-302e**, transmission line **304**, and coupling strips **306a-306e** of the conventional notch filter **300** may each be individual and separate components. Each component may need to be individually assembled and tuned for the conventional notch filter **300** to achieve a desired frequency rejection. Due to the amount of separate components and involved tuning process, the conventional notch filter **300** may have a complex and time-consuming assembly process.

FIG. 5 illustrates an embodiment of a non-resonant node filter **500**. The non-resonant node filter **500** may include six comline resonators **502a-502f** and six non-resonant nodes **504a-504f**. The six non-resonant nodes **504a-504f** may be coupled to each other by five mainline coupling elements **506a-506e**. The non-resonant nodes **504a-504f** may be configured to resonate at frequencies far outside of a desired passband. By not resonating in the desired passband, the six non-resonant nodes **504a-504f** and five mainline coupling elements **506a-506e** may form a mainline. A signal may be input to the mainline via an input port **508** connected to non-resonant node **504a**. A filtered signal may exit the mainline via an output port **510** connected to non-resonant node **504f**.

The six comline resonators **502a-502f** may be coupled to the mainline via six comline coupling elements **512a-512f**. Comline coupling element **512a** may couple comline resonator **502a** to non-resonant node **504a**. Comline coupling element **512b** may couple comline resonator **502b** to non-resonant node **504b**. Comline coupling element **512c** may couple comline resonator **502c** to non-resonant node **504c**. Comline coupling element **512d** may couple comline resonator **502d** to non-resonant node **504d**. Comline coupling element **512e** may couple comline resonator **502e** to non-resonant node **504e**. Comline coupling element **512f** may couple comline resonator **502f** to non-resonant node **504f**. The mainline coupling elements **506a-506f** and comline coupling elements **512a-512f** may be the same type of coupling elements.

While six comline resonators, six non-resonant nodes, five mainline coupling elements, and six comline coupling elements are shown, the number of comline resonators, non-resonant nodes, mainline coupling elements, and comline coupling elements may vary based upon a desired capability of the non-resonant node filter **500**.

The comline resonators **502a-502f**, non-resonant nodes **504a-504f**, mainline coupling elements **506a-506e**, and comline coupling elements **512a-512f** may be integral parts of the non-resonant node filter **500**. The integral parts of the non-resonant node filter **500** may allow the non-resonant node filter **500** to be less complex to assemble and tune than the conventional comline filter **100** and conventional notch filter **300**.

FIGS. 6A and 6B illustrate examples of frequency responses that may be achieved with the non-resonant node filter **500**. The example of FIG. 6A may have a rejection region **604** below a passband region **602**. The rejection region **604** may be a range of frequencies that may be minimized based on a tuning of the non-resonant node filter **500**. The frequencies in the passband region **602** may not be significantly filtered by the non-resonant node filter **500** when the non-resonant node filter **500** is tuned to the rejection region **604**.

The example of FIG. 6B may have a rejection region **608** above a passband region **606**. The rejection region **608** may be a range of frequencies that may be minimized based on a different tuning of the non-resonant node filter **500** than the example of FIG. 6A. The frequencies in the passband region **606** may not be significantly filtered by the non-resonant node filter **500** when the non-resonant node filter **500** is tuned to the rejection region **608**. In this way, the non-resonant node filter **500** may reject different ranges of frequencies based upon the tuning of the non-resonant node filter **500**. The components of the non-resonant node filter **500** may not need to be redesigned for the non-resonant node filter **500** to reject different ranges of frequencies, only the tuning of the non-resonant node filter **500** may need to be adjusted. The tuning of the non-resonant node filter **500** may be adjusted by tuning the frequencies of the comline resonators **502a-502f** and/or the values of the comline coupling elements **512a-512f**. Further modification to the design of the non-resonant node filter **500** may not be necessary to shift the rejection regions above or below a passband region.

According to the foregoing, various exemplary embodiments provide for a filter that may be easier to assemble and tune than conventional filters. Further, various exemplary embodiments provide for a filter that may be easier to configure to reject different ranges of frequencies than conventional filters.

Although the various exemplary embodiments have been described in detail with particular reference to certain exemplary aspects thereof, it should be understood that the invention is capable of other embodiments and its details are capable of modifications in various obvious respects. As is readily apparent to those skilled in the art, variations and modifications can be affected while remaining within the spirit and scope of the invention. Accordingly, the foregoing disclosure, description, and figures are for illustrative purposes only and do not in any way limit the invention, which is defined only by the claims.

What is claimed is:

1. A filter configured to operate in an operational frequency range, comprising:
a mainline, disposed along a central axis, comprising at least one non-resonant node, wherein the at least one

5

- non-resonant node is configured to resonate in a frequency range outside of the operational frequency range of the filter;
- a combline filter coupled to the mainline, wherein the combline filter is configured to resonate in a frequency range within the operational frequency range of the filter, the combline filter comprises a first subset of combline resonators and a second subset of combline resonators, and the first subset of combline resonators and the second subset of combline resonators are located on opposite sides of the central axis;
- an input port coupled to the mainline; and
- an output port coupled to the mainline.
2. The filter of claim 1, wherein a non-resonant node filter is tuned to a rejection region.
3. The filter of claim 2, wherein the rejection region is below a passband region of the combline filter.
4. The filter of claim 2, wherein the rejection region is above a passband region of the combline filter.
5. The filter of claim 1, wherein the mainline comprises at least two non-resonant nodes.
6. The filter of claim 5, wherein a first combline resonator of the first subset of combline resonators is coupled to a first non-resonant node, and a second combline resonator of the second subset of combline resonators is coupled to a second non-resonant node.
7. The filter of claim 1, wherein the mainline comprises six non-resonant nodes.
8. The filter of claim 7, wherein the six non-resonant nodes are coupled to each other by five mainline coupling elements.
9. The filter of claim 1, wherein the filter is configured to reject a first range of frequencies within the operational frequency range based on a first tuning of the filter, and reject a second range of frequencies within the operational frequency range based on a second tuning of the filter.
10. The filter of claim 1, wherein the at least one non-resonant node and the combline filter are integral to the filter.
11. The filter of claim 1, wherein the input port is coupled to the at least one non-resonant node.
12. The filter of claim 1, wherein the output port is coupled to the at least one non-resonant node.
13. The filter of claim 1, further comprising:
- combline coupling elements that are configured to couple the combline filter to the at least one non-resonant node.
14. A method for manufacturing a filter configured to operate in an operational frequency range, the method comprising:
- forming a mainline, disposed along a central axis, comprising at least one non-resonant node, wherein the at least

6

- one non-resonant node is configured to resonate in a frequency range outside of the operational frequency range of the filter;
- forming a combline filter comprising a first subset of combline resonators and a second subset of combline resonators coupled to the mainline, wherein the first subset of combline resonators and the second subset of combline resonators are located on opposite sides of the central axis and the combline filter is configured to resonate in a frequency range within the operational frequency range of the filter;
- forming an input port coupled to the mainline; and
- forming an output port coupled to the mainline.
15. The method of claim 14, wherein the mainline comprises at least two non-resonant nodes.
16. The method of claim 15, further comprising:
- coupling a first combline resonator of the first subset of combline resonators to a first non-resonant node; and
- coupling a second combline resonator of the second subset of combline resonators to a second non-resonant node.
17. The method of claim 14, further comprising:
- rejecting, with the filter, a first range of frequencies within the operational frequency range based on a first tuning of the filter; and
- rejecting, with the filter, a second range of frequencies within the operational frequency range based on a second tuning of the filter.
18. The method of claim 14, wherein the at least one non-resonant node and the combline filter are integral to the filter.
19. A filter configured to operate in a plurality of frequency ranges, the filter comprising:
- a plurality of combline resonators that are configured to resonate in a passband region, wherein the passband region is a range of frequencies that are not significantly filtered by a combline filter;
- a plurality of non-resonant nodes disposed along a central axis that are configured to resonate in a rejection region, wherein the rejection region is a range of frequencies that are minimized by notch filters, wherein subsets of the plurality of combline resonators are located on opposite sides of the central axis; and
- a plurality of combline coupling elements that are configured to respectively couple each combline resonator to a respective non-resonant node.
20. The filter of claim 19, wherein the range of frequencies in the passband region are not significantly filtered when a non-resonant node filter is tuned to the rejection region.
